UNITED STATES PATENT OFFICE.

ROBERT E. LEVE, OF NEW YORK, N. Y.

ELECTRIC CLOTH-CUTTING MACHINE.

SPECIFICATION forming part of Letters Patent No. 678,263, dated July 9, 1901.

Application filed February 8, 1901. Serial No. 46,518. (No model.)

To all whom it may concern:

Be it known that I, ROBERT E. LEVE, a citizen of the United States, residing at New York, in the borough of Manhattan and State 5 of New York, have invented certain new and useful Improvements in Electric Cloth-Cutting Machines, of which the following is a specification.

My invention relates to electric cloth-cutting machines, by which a great many layers of cloth may be cut out simultaneously according to the patterns required for the garments to be made.

The objects of the invention are to provide a machine of the said class by which through the act of grasping the handle to push the machine along the cutting-blade will be automatically reciprocated at a high speed; also, to provide a cutting-blade which 20 makes a clean cut through the cloth without fraying out the edges, this being accomplished by imparting only a short reciprocating motion to the cutting-blade, so that its lower end preferably does not rise above the lower layer 25 of cloth, and also to provide the handle with a special switch which is automatically closed by the act of grasping the handle. The machine is also durable, practical, and highly efficient and is so constructed that various 30 forms of knives or cutting-blades may be used.

With these ends in view my invention consists, first, of an electric cloth-cutting machine which comprises a base-plate adapted to move under the layers of cloth, a standard rising 35 from said base and provided with side guide-plates, a motor supported by a frame carried by the standard, a reciprocating carrier connected with the motor and supporting a cutting-blade which is guided between said 40 guide-plates, said cutting-blade moving into a slot in the base-plate and preferably having a motion no greater than the thickness of the plate, a handle on the motor-frame, and means for operating said motor.

45 The invention further consists of removable guide-plates for the cutting-blade attached to the standard and provided with beveled or knife edges for entering into the cut made in the cloth and clearing the way for the 50 easy passage of the standard, the guide-plates, and the cutting-blade through the layers of cloth.

The invention also consists of a stationary handle for electric cloth-cutting machines in which an electric current is the medium for 55 operating the cutting device, and a movable part or member carried by the handle and provided with a connector normally out of contact with the electric connection through which the operating-current flows, thereby 60 arresting the motion of the cutting device, but capable of completing the electric circuit by the pressure of the hand of the operator, thereby again putting the cutting device in motion, the said connection being automatically 65 broken when the pressure of the hand is removed, thereby stopping the motion of the cutting device.

The invention consists, further, of an adjustable upright supported on the frame of 70 the machine and provided with a presser-foot at its lower end and a guard-plate suitably stayed and extending upwardly from the toe of the presser-foot; and the invention further consists of certain details of construction and 75 combinations of parts to be hereinafter described in detail and then pointed out in the claims.

In order that my invention may be more fully understood, I will now proceed to describe the same with reference to the accompanying drawings, in which—

Figure 1 is a side elevation of my improved electric cloth-cutting machine. Fig. 2 is a front elevation of the same, showing portions 85 of the base-plate and guard-plate broken away. Fig. 3 is a cross-section on line 3 3, Fig. 2. Fig. 4 is an enlarged longitudinal section of the handle, showing the switch. Fig. 5 is a detail perspective view showing a 90 modification. Fig. 6 is a transverse section of Fig. 5 on line 6 6; and Fig. 7 is a detail view of a portion of the standard with the outer guide-plate removed and the detachable inner guide-plate, which may be straight-edged, as shown in full lines, when used as in Fig. 2, or it may have rounded cutting-teeth, as shown in dotted lines, when used in the modification shown by Fig. 5, or it may have saw or other teeth, according to the form 95 of teeth which the cutting-blade may be provided with.

Similar letters of reference indicate corresponding parts throughout the drawings.

The base-plate A of the machine slants at top to either or all sides, but preferably toward the front lifting edge *a*, so that at the place from which the fixed standard B rises 5 the base-plate is thickest. Bolted or otherwise suitably secured to the upper end of the standard B is a block C, above which is a block C', both of which blocks are on the motor-casing D and, together with the same, 10 form the frame of the machine. The motor *d* is inclosed within the casing D, and being of any well-known and serviceable type is not illustrated in detail.

E indicates the reciprocating cutting-blade, 15 which moves within guide-plates F F', forming a part of and attached to one side of the standard B. As shown in detail in Fig. 7, the inner guide-plate F, which is attached directly against the rabbeted inner side of 20 the standard B, is provided with two or more steady-pins *f*, which, as shown in Fig. 3, enter corresponding holes in the said standard, said plate F being firmly fixed to the standard by means of countersunk screws *f*². Fixed 25 to standard B by means of countersunk screws *f*³, which enter behind the rabbet-groove *f*⁴, in which the plate F is seated, is the other guide-plate F', which is separated at a suitable distance from the plate F, so as to provide 30 a groove or space in which the cutting-blade E may reciprocate. The lower end of the cutting-blade is provided, as shown by dotted lines in Figs. 1 and 7, with a longitudinal slot *f*⁵, through which the lower steady- 35 pin *f* passes, as well as through the plate F, as stated. The front edges of the guide-plates F F' are knife-edged or beveled, and the sharpened edge of the cutting-blade projects a suitable distance beyond the same, so that 40 it can form a clean cut through the cloth.

G indicates the blade-carrier, which is adapted to reciprocate in the blocks or ears C C' on the motor-casing D and which is provided with a split clamp *g*, into which the upper end of 45 the cutting-blade E is inserted and secured by a set-screw *e*, whereby through the medium of the pin-and-slot connection at *f*⁵ the cutting-blade is moved in a longitudinal path. The blade-carrier G is provided with a trans- 50 verse chamfered guideway *g*' for a slide-block *g*², which receives a crank or wrist pin *h* on the head or disk *h*', attached directly on the end of the armature-shaft D'. Through the medium of the described connection of the 55 armature-shaft with the blade-carrier a direct thrust and pull is imparted to the cutting-blade, as there is no lost motion and no unnecessary connections, the wrist-pin acting directly in line with the cutting-blade itself.

60 I I' indicate the leading-in wires, running from a handle J, fixed to the bottom of the motor-casing by means of a screw or screws *j*', which pass through the shank *j*. The wires I I' are led through the inner end of the handle and are connected with contacts *k*, fixed 65 on the bottom of a deep longitudinal recess *k*', formed in the wooden or other non-con-

ducting handle J. (See Fig. 4.) A movable member or non-conducting handle J', which forms a portion of the handle, moves within 70 and corresponds to the said recess *k*', it being forced outwardly by means of helical or other springs *k*², confined within the recess against keepers *k*³, projecting from the handle inwardly over the ends of the said movable 75 member. On firmly grasping the handle the movable member will yield to the pressure. Knife-contacts *k*⁴ are secured to the inner side of the movable member, so as to oppose the fixed contacts *k* and to form contact there- 80 with when the movable member is pressed in, thereby forming a switch and closing the electric circuit, the current for which is supplied in any suitable manner from the main con- 85 ducting-wires I² I³, leading from any suitable source of electric power. The wires I² I³ are led through the inner end of the handle and connected with the movable contacts *k*⁴.

A slot or recess *l* is formed in the base-plate A just below the guide-plates F F', in which 90 the lower end of the cutting-blade E moves, said blade preferably never leaving the upper surface of the base-plate, so that its lower extremity cannot pass above the lower layer of cloth. The motion imparted to the cutting-blade by the means for converting the 95 rotary motion of the armature into the reciprocating motion of the said cutting-blade is preferably so limited that the lower end of the blade simply moves up and down in the slot *l*. 100

For holding the layers of cloth down the machine is provided with a slotted presser-foot M, the toes *m* of which are turned up, so as not to catch on the top layer of cloth, said presser-foot being vertically adjustable by 105 means of a supporting bar or upright N, to which it is secured, and the latter being in turn secured rigidly to the blocks or ears C C' by a thumb-screw *n*, which passes through a longitudinal slot *n*' in the said bar. The 110 opening in the presser-foot receives the standard and contiguous side parts.

To protect the hands against injury by the cutting-blade, a guard-plate O is attached at its lower end to the toe of the presser-foot M, 115 extends upwardly in front of the cutting-blade, and is attached at its upper end to the upper end of the upright or bar N.

A modification is shown in Figs. 5 and 6, in which a cutting-blade E', which is supplied 120 with a series of curved or scalloped teeth *e*', is substituted for the blade E, while for the guide-plate F a guard-plate F², which is pro- 125 vided with corresponding teeth *e*², is substituted, said guard-plate F² being wider than the guide-plate F, so that the teeth thereof will lie alongside the teeth of the cutting-blade, whereby the said teeth combine to produce a shear cut.

The relative width of the plates F and F² 130 are indicated, respectively, by full and dotted lines in Fig. 7. Of course other shapes of teeth may be used as may be found best suited for the kind of cloth to be cut.

To operate the machine, the operator firmly grasps the handle J, so as to close the electric circuit through the action of the switch formed by movable member J' and contacts 5 k⁴, the current flowing around the armature and imparting a reciprocating motion to the cutting-blade E so long as the proper pressure on the said movable member is maintained. The cutting-blade having now been 10 set in motion, the front edge a of the base-plate is moved along the table and under the layers of cloth to be cut, the operator still pressing the machine forward and carefully following the lines laid out on the cloth, so 15 that the cutting edge of the blade will cut out the proper shape. When the cloth has been cut, the operator relaxes his grasp on the handle, so that the circuit may be automatically broken and the motion interrupted.

20 The described cloth-cutting machine is under the full control of the operator and can be quickly started and stopped, the same being accomplished in a sense automatically, as the very act of tightly grasping the handle to 25 push the machine along to the work starts the motor. It is evident that a switch can be arranged on the handle which is non-automatic.

While I have shown and preferably construct a cloth-cutting machine in which the 30 cutting-blade does not rise above the base-plate, I do not restrict myself to the same, as it is possible to use the other new features of my invention with a cutting-blade which has a certain movement above the base-plate.

35 Having thus described my invention, what I claim as new is—

1. In an electric cloth-cutting machine, the combination of a movable supporting-frame, a cutting device mounted thereon, an electric 40 motor connected with the cutting device, a stationary handle, and a movable part or member carried by the handle provided with a connector normally out of contact with the electric connection through which the operating-current flows, thereby arresting the motion of the cutting device, but capable of completing the electric circuit by the pressure of the hand of the operator, thereby putting the cutting device in motion, the said connec-

tion being automatically broken when the 50 pressure of the hand is removed, thereby stopping the motion of the cutting device, substantially as set forth.

2. In an electric cloth-cutting machine, the combination of a base-plate adapted to move 55 under the layers of cloth, a standard provided with a guide, a frame supported by the standard, a motor in the frame, and a reciprocating cutting-blade suitably connected at its upper end with the motor and received in said guide, 60 said base-plate having a slot, receiving the free lower end of the cutting-blade, and said cutting-blade having a motion no greater than the thickness of the plate, so that the said end of the cutting-blade does not rise above the 65 base-plate, substantially as set forth.

3. In an electric cloth-cutting machine, the combination of a base-plate adapted to move under the layers of cloth, a standard mounted on the base-plate, removable guide-plates 70 spaced at a suitable distance apart and secured to the standard, one of said plates being fixed against the standard in a rabbet-groove thereof, while the other is fixed directly against the side of the standard, a single reciprocating cutting-blade guided in the space between said removable guide-plates, and an electric motor connected with said cutting-blade, substantially as set forth.

4. In an electric cloth-cutting machine, the combination of a movable supporting-frame, an electric motor, a crank-pin on the shaft of the motor, a reciprocating carrier guided in the frame and provided with a transverse guideway, a slide guided in the guideway and 85 provided with a hole for receiving said crank-pin, and a cutting-blade attached to said carrier in a plane with the crank-pin so as to receive the direct thrust and pull of said crank-pin, substantially as set forth.

90 In testimony that I claim the foregoing as my invention I have signed my name in presence of two subscribing witnesses.

ROBERT E. LEVE.
